Montford Morrison,
By Ayrenforth Lee, Chitton Mills,
Att'd.

UNITED STATES PATENT OFFICE.

MONTFORD MORRISON, OF OAK PARK, ILLINOIS, ASSIGNOR, BY MESNE ASSIGNMENTS, TO VICTOR X-RAY CORPORATION, OF CHICAGO, ILLINOIS, A CORPORATION OF NEW YORK.

HIGH-POTENTIAL ELECTRICAL SYSTEM.

Application filed July 23, 1920. Serial No. 398,536.

My invention relates to electrical systems employing high potential current of such strength that dangerous, or deadly, results occur to living objects approaching close to, or coming in contact with, the electric-current-conducting elements traversed by the high potential current, or inanimate objects positioned relatively closely to the apparatus may cause short circuits to be produced; 10 present day X-ray apparatus commonly involving such a system, wherein the current for operating the X-ray tubes is often maintained as high as 100,000 volts; my invention having been devised for embodiment more 15 particularly in such apparatus, though not to the exclusion of its use in apparatus for other purposes.

Particularly in X-ray apparatus it is unavoidable, owing to the conditions presented, 20 that certain of the elements traversed by the high potential current, be so exposed that there is danger of the patient or operator, approaching so closely to such elements as to receive an electric discharge of such intensity as to severely shock, and sometimes 25 fatally, the patient or operator, as the case may be, and a fatal result is almost certain to occur should the patient, or operator, come in contact with such elements.

30 My primary object is to provide in a high potential system wherein the results above-referred-to are possible, for the preventing of the shocking of a living object, at least to a degree which would be injurious, should 35 such object approach the elements traversed by the high potential current and the production of undesirable short-circuits in the apparatus in the event of the movement of an inanimate object into close proximity 40 thereto.

Generally stated, my invention consists in providing means which will automatically operate, should an object which would disturb the electric field, approach the elements 45 carrying the high potential current to within a distance thereof beyond which, should the object approach such elements, the electric discharge taken by such object would be of undesired intensity, to cause the flow of such 50 high potential current to be arrested, and preferably by breaking the low tension circuit from which the high potential current is derived.

Referring to the accompanying drawings:— 55

Figures 1, 2, 3 and 4 show, by views in the nature of diagrams, the application of my invention to a plurality of X-ray systems, the embodiments shown being by way of illustration only, the invention being applicable to other systems the use in connection with which, it is my purpose to claim my invention as well as those illustrated.

Referring to Fig. 1; 10 represents a rectifier, which may be of any suitable construction and adapted to supply direct current to an X-ray tube represented at 11 and which may be of any suitable construction.

The rectifier shown is provided with the four contacts 12, 13, 14 and 15 which are 70 represented as stationary and with which co-operate the current-conducting arcs 16 and 17 carried by a rotating disk 18 driven through the medium of a shaft 19 from a motor 20 which is driven at such speed, as is 75 well understood in the art, as to cause the alternating current delivered to the contacts 14 and 15 as hereinafter described, to have uni-directional flow through the tube 11, the current being delivered to said tube through 80 the medium of wires 21 and 22 connected respectively with the terminals of the tube and with the contacts 13 and 12.

The current from which the tube-operating direct current is supplied, is supplied 85 through the wires 23 and 24 which lead to any suitable source of supply as for example an alternating current supply of 220 volts, the wires 23 and 24 connecting with the ends of the primary 25 of a high tension transformer 26, the secondary of which is represented at 27 and the heavy insulation between the primary and secondary at 28, this being shown diagrammatically. The secondary 27 is connected at its ends with the contacts 14 and 15 as through the medium of the wires 29 and 30, the transformer 26 being of such construction as to step-up the current to the desired high potential for the work to be performed. 95

The motor 20 is shown as supplied with current from the line wires 23 and 24 arranged in parallel with the transformer 26, the wires for conducting current to the motor being represented at 31 and 32 and connected with the wires 23 and 24 respectively. 100 105

The main line wire 24 is shown as having interposed therein switches 33 and 33^a of any suitable type, the switch 33 being one which is required to be thrown by hand to a position for closing the circuit through the primary 25, and maintained in circuit-closing condition by the action of a magnetic coil 34, the switch 33 moving to open condition when the coil 34 is deenergized.

In accordance with the illustrated embodiment of my invention, I provide an electrostatic relay represented at 35 and shown as comprising a pair of disks 36 and 37 supported from a base 38 and out of electrical contact with each other, one of these disks being supported from the upright 39 and the other from a depending arm 40 pivoted to the upper end of an upright 41, there being provided, to extend into the space between the disks 36 and 37 and out of contact therewith, a contact strip 42 on the base 38. The disk 36 is shown as electrically connected with the secondary 27 of the transformer 26 midway between the ends of the windings of said secondary, as by wire 43, and the disk 37 is shown as connected with a wire 44 the opposite ends of which are connected with one end of the primary 25 of the transformer 26 as represented at 45 and its opposite end to one end of the coil 34. The opposite end of the coil 34 connects by a wire 46 with the contact 42, the wire 46 connecting with one end of a resistance coil 47, the opposite end of which is connected with the line wire 24 through the medium of the wire 48.

The apparatus is shown as including a condenser represented at 49 which is preferably of the so-called variable type to compensate for different conditions of electrostatic capacity, as hereinafter explained, this condenser being shown as interposed in a wire 50 connecting one of the electrodes of the tube 11 with the disk 37.

The parts of the electrostatic relay normally occupy the positions represented, wherein the disk 37 is out of contact with the contact 42, and the function of this relay, in the particular arrangement shown, is to short-circuit the holding coil 34 in the event of the approach of an object to within a predetermined distance of the elements traversed by the high potential current, by the movement of the disk 37 into engagement with the contact 42.

In the normal operation of the apparatus shown so long as no object approaches any of the elements along which the high potential current travels, the electrostatic relay remains inactive, assuming that the current is balanced at both sides of the high potential current, but as soon as an object approaches any of such elements to within a certain distance thereof, an electrostatic field will be caused to be produced across

the gap between the disks 36 and 37 producing a movement of the disk 37 into engagement with the contact 42, thereby short-circuiting the coil 34, the circuit thus established being from the wire 24 through wire 48, coil 47, wire 46, contact 42, disk 37, arm 40, wire 44 and wire 23, it being understood from the drawings that the circuit supplying current to the coil 34, in the normal operation of the apparatus, is from wire 24 through wire 48, coil 47, coil 34, wire 44, terminal 45 and wire 23.

Upon the approach of an object to any one of the elements traversed by the high potential current, such object takes an electrostatic charge, which causes current to flow through the wire 23, which is substantially grounded in view of the light insulation maintained between the generator at the power house and the earth, the wire 44, arm 40, disk 37, across the gap between this disk and the disk 36, to the latter, wire 43 to secondary 27, thence to the element carrying the high potential current and adjacent to which said object extends and through said object to the ground, the current traversing the wires 29 or 30 depending on the position of the rotating arcs 16 or 17. The operation of the electrostatic relay is dependent on the passage of a predetermined amount of current through the relay. It is preferred that the relay operate as stated, upon the passage therethrough of a relatively small amount of current, as for example one-millionth of an ampere, though this may be varied as desired, it being understood that upon operating the relay as stated the switch device 33, by reason of the weakening of the coil 34, will automatically move to open condition and break the supply circuit comprising the line wires 23 and 24.

It will be understood that a relay operated by such a small amount of current as not to be sensed by a living object may be provided and thus the slightest discomfort to a living object may be prevented.

It often happens in the installation of high potential apparatus that the proximity of objects or parts of the structure to the elements over which the current flows to the tube, is such that one side of the high potential circuit is delivering an electric discharge unbalanced as compared with the other side thereof. In other words the wire 21, or wire 22 may be delivering an electric discharge through such object, which would serve to produce an unbalanced condition in the electrostatic relay. This may be compensated for in any desired way in order that both sides of the high potential circuit be in balance, the means provided in Fig. 1 being the condenser 49 hereinbefore referred to and which is shown as so located as to balance the electric flow, assumed to be present at the side of the high potential circuit

adjacent the wire 21, existing, as for example, by reason of the proximity of an object stationary relative to this side of the high potential circuit and capable of taking an electric charge. It will be understood that if the electric discharge to be compensated for is at the opposite side of the high potential circuit, viz, at that side at which the wire 22 is located, the condenser 49 would 10 be connected with the opposite side of the circuit, as for example at the opposite side of the tube.

In the arrangement illustrated in Fig. 2 I have shown my invention as embodied in a system employing an X-ray tube of the alternating-current type, with electrical means for heating the cathode, the arrangement shown further embodying a transformer of a type in which the secondary is grounded 20 between the ends thereof to the primary, this being a condition commonly found in installations now in use.

The transformer last-referred-to is represented at 51, its primary being indicated at 52, its secondary at 53 and the heavy insulation interposed therebetween, at 54, the wire connecting the secondary 53 between the ends of its windings, with the primary 52 being indicated at 54. The secondary 53 is connected by a wire 55 with the anode terminal 56 of the tube represented at 57 and by the wires 58 and 59 with the terminals 60 of the cathode of the tube, the other terminal 61 of the cathode being connected with a 35 wire 62. It will be understood that, in accordance with common practice, low tension current is supplied through the wires 58 and 62 to the heating filament of the tube and that the high potential current traverses the wires 58 and 59.

The main-line supplying wires, corresponding with the wires 23 and 24, are represented at 63 and 64, these wires connecting with the terminals of the primary 65 of a transformer 66 the secondary of which is represented at 67 and the interposed heavy insulation, at 68. The wire 64 has interposed therein switches 69 and 69^a corresponding with the switches 33 and 33^a, the holding coil for the switch 69 being represented at 70 and the resistance corresponding with the resistance coil 47, at 71. The ends of the secondary 67 are connected with the ends of the primary 52 of the transformer 51 by the wires 72 and 73, the secondary 67 being connected by a wire 74 with the disk 36 of an electrostatic relay such as shown in Fig. 1. The contact 42 of the relay is connected by a wire 75 with one end of the holding coil 70 and one end of the resistance coil 71. The arm 40 is connected by a wire 76 with one end of the primary 65, and by a wire 77 with the anode terminal 56, the wire 77 having interposed therein a condenser 49 corresponding with that of Fig. 1.

The current for supplying the heating circuit of the tube is supplied through the wires 63 and 64 by the connection therewith of the wires 78 and 79 connecting with the primary 80 of a transformer 81, the secondary of 70 which is represented at 82. The primary and secondary are separated by heavy insulation diagrammatically represented at 83. The wire 79 is shown as provided with a switch device 84 and the wire 78 with a current regulator 85. The purpose of the transformer 81 is to step-down the current to relatively low voltage as compared with the supply current, in accordance with common practice, the voltage being reduced to about 80 ten volts.

The transformer 66 is provided merely for the purpose of insulating the primary 52 from the earth, and consequently the wire 74, from the earth, and not necessarily to either step-up or step-down the current.

The wire 74 being in effect connected with the secondary 53, the functioning of the electrostatic relay 35 of Fig. 2 is the same as 90 that in Fig. 1, and therefore detailed description of its operation appears to be unnecessary.

The provision of the step-down transformer 81 operates to produce an unbalanced condition at the side of the high potential circuit between the cathode and the secondary 53, which is shown to be balanced by the provision of the condenser 49, in order that the relay 35 may present the desired sensitiveness to operation.

In the arrangements shown in Figs. 3 and 4, which present an example wherein relatively large unbalanced currents in the high potential circuit would be produced, provision is made for causing such current to be diverted from passage through the relay and the balancing through the relay of only minor currents which if not compensated for would produce an undesirable unbalanced 110 condition.

Referring particularly to the arrangement shown in Fig. 3, the X-ray tube illustrated is of the direct current, hot-cathode type (Coolidge tube), the tube being represented at 86, its anode terminal at 87 and its cathode filament terminals at 88 and 89. The source of current supplied being alternating-current, the main wires of which are represented at 90 and 91, a rectifier represented at 92 is provided, its stationary contacts being represented at 93, 94, 95 and 96 and its rotating arcs, carried by the rotating disk 97, at 98 and 99. The contact 94 is connected with the terminal 87 by the wire 100, the contact 96 is connected with the terminal 89 by a wire 101, the contact 95 is connected by a wire 102 with one end of the secondary 103 of a heavy insulation transformer 104, the primary of which is repre- 130

5   sented at 105 and the heavy insulation there-
of at 106; and the contact 93 is connected
by a wire 107 with the other end of the
secondary 103. The transformer 104, as
well as the corresponding transformer of
Fig. 4, is of the center-grounded type as
explained of the transformer 51 of Fig. 2, its
center wire being represented at 108, which
connects with the primary 105 by a wire
108^a. This arrangement also involves the
provision of a transformer 109 corresponding
to, and functioning the same as, the
transformer 66 of Fig. 2, its secondary be-
ing represented at 110 and connected with
15   the ends of the primary 105 by the wires
111 and 112, its primary at 113 and the
heavy insulation therebetween at 114, the
ends of the primary 113 being connected
with the wires 90 and 91, the wire 91 having
20   interposed therein switches 115 and 115^a
corresponding with the switches 69 and 69^a,
the holding coil for the switch 69 being re-
presented at 116 and the resistance coil, cor-
responding to the coil 47, at 117. The elec-
25   trostatic relay 35 has its disk 36 connected
by a wire 118 with the wire 112, and its
disk 37 with the terminal 87, by a wire 119,
and with the holding coil 116 by the wire
120.
30   In this arrangement the means for supply-
ing low-tension current to the cathode-heating
filament of the tube involves the wires
121 and 122 connected with the line wires
90 and 91, respectively, and with the ends
35   of the primary 123 having the secondary
124 which is heavily insulated from the pri-
mary 123 by the insulation diagrammatical-
ly illustrated at 125, the wire 122 contain-
ing a current-regulating device 126 and be-
40   ing grounded through the wire 127. The
transformer of which the primary 123 is
a part, is a mere insulating transformer,
its secondary 124 being connected with the
primary 126 of a step-down transformer,
45   through the medium of the wires 127 and
128, the secondary of this step-down trans-
former being represented at 129 and the
heavy insulation therebetween being re-
presented diagrammatically at 130. The ends
50   of the secondary are connected with the
terminal 88 of the tube. The wire 108 con-
nects with the primary 126.

The relay 35 functions in the same man-
ner as explained of the relay 35 in Fig. 1,
55   and detailed description of the operation
thereof appears to be unnecessary.

As will be understood by those skilled in
the art there is produced an electric field
across the space between the primary and
60   secondary 126 and 129 respectively which
induces a current which flows between the
primary and secondary, over the wire 101
to the contact 96 and through one or the
other of the arcs 98 and 99 to the contacts
65   93 or 95, depending upon the position of

the arcs, thence to the primary 103, wire
108 and back to the primary 126, but by
reason of the arrangement shown this cur-
rent thus derived and which may be of fair-
ly substantial amount, is not caused to trav-
70   erse the relay 35 thereby rendering un-
necessary the balancing of the same through
the relay, and this arrangement is espe-
cially desirable where currents of relatively
large magnitude are set up in the apparatus. 75

The arrangement shown presupposes the
existence of such conditions as would cause
an unbalanced condition in the relay, if not
compensated for, the arrangement shown
being based upon an electric discharge
80   through the side of the high potential cir-
cuit between the cathode end of the tube and
the secondary 103, as for example by rea-
son of the permanent location of an object
85   sufficiently close to this side of the high
potential circuit as to create such electric
discharge by reason of the electrostatic ca-
pacity of the object, and to correct this, a
90   condenser represented at 132 and corre-
sponding with the condenser 49 is inter-
posed in the wire 119.

The arrangement shown in Fig. 4 is iden-
tical with that shown in Fig. 3 except that
means for compensating the unbalanced effect
95   in the high potential circuit created by the
existence of the transformer of which the
primary 126 is a part, and to this end a wire
133 connects the wire 108 with the contact
94 and has interposed therein a condenser
100   represented at 134 of a capacity sufficient
to balance the current set up between the
primary 126 and secondary 129. The con-
denser 132 in this case would be provided
for the same purpose as the condenser 132 of
105   Fig. 3, viz, to compensate for any condition
which would otherwise produce an un-
balanced effect on the relay 35.

While I have shown certain electrical ar-
rangements embodying my invention, I do
not wish to be understood as intending to
limit it thereto as the same may be variously
modified and altered without departing
110   from the spirit of my invention, it being my
intention to claim my invention as fully and
completely as the prior state of the art will
115   permit.

What I claim as new and desire to secure
by Letters Patent, is:

1. Electrical apparatus comprising, in
combination, a high potential circuit, a low
potential circuit for energizing said first
named circuit, a pair of plates in spaced re-
lation each connected to said high potential
circuit and one thereof movable toward the
other when the circuit is unbalanced elec-
120   trically, a contact in the path of move-
ment of said plate, and means connected to
said plate and contact adapted to de-ener-
gize said low potential circuit, upon closing
125   of said contact.

2. Electrical apparatus comprising, in combination, a high potential circuit, a transformer having its secondary included in said circuit, a low potential current supply means connected to the primary of said transformer, electrically operated current arresting means adapted to break the low potential circuit, an electrostatic device comprising two plates, a connection from one plate to the middle of said secondary and the second plate connected to said high potential circuit adjacent one end of the secondary, means whereby said plates may remain spaced when the circuit on each side thereof is in electrostatic balance and may have the space reduced when said balance is disturbed by approach of an object to change the capacity of said first named circuit, a contact in said space, and means connecting said contact and one of said plates with said current arresting means.

MONTFORD MORRISON.
